COMBINED DIAL PLATE AND RING FOR A TIMEPIECE FACE

Sadao Fujinami, Hatogaya, Japan, assignor to Orient
Tokei Kabushiki Kaisha (also trading as Orient Watch
Co., Ltd.), Tokyo, Japan

Filed Feb. 29, 1972, Ser. No. 230,551

Term of patent 14 years

Int. Cl. D10—07
U.S. Cl. D10—123

The figure is a top plan view of a combined dial plate and ring for a timepiece face showing my new design.

In the back and edge views the combined dial plate and ring is conventionally plain and of no appreciable thickness.

I claim:

The ornamental design for a combined dial plate and ring for a timepiece face, as shown and described.
